UNITED STATES PATENT OFFICE.

JOSEPH M. MERROW, OF MERROW, CONNECTICUT.

CROCHETING OR OVERSEAMING MACHINE.

SPECIFICATION forming part of Letters Patent No. 428,508, dated May 20, 1890.

Application filed September 12, 1887. Serial No. 249,491. (No model.)

To all whom it may concern:

Be it known that I, JOSEPH M. MERROW, a citizen of the United States, residing at Merrow, in the county of Tolland and State of Connecticut, have invented certain new and useful Improvements in Crocheting or Overseaming Machines, of which the following is a specification, to wit:

My invention relates to feeding mechanism and new and useful combinations therewith.

The object of my invention is to produce new and improved ornamental crocheted finish or border by machinery upon fabrics in general, but particularly upon knitted fabrics which have heretofore been ornamentally finished by hand. I accomplish this object by means of the improvements hereinafter described, illustrated, and claimed, consisting in new mechanism and new combinations of mechanism.

In the drawings annexed hereto and forming a part of this specification, Figure 1 is a vertical side view of a portion of a crocheting or overseaming machine, showing the feeding mechanism. Fig. 2 is a bottom view of a similar machine reduced in size. Fig. 3 is a detached vertical side view of a portion of the feeding mechanism, showing the pattern-wheel. Fig. 4 is a vertical side view of the feed-dog and lock and operating parts immediately connected therewith. Fig. 5 is a plan view of a portion of the work-plate, showing the finger-plates and top of the feed-dog. Fig. 6 is a top view of the finger-plate lock detached, part being in section. Fig. 7 is a vertical view of a section of the work-plate and finger-plates on line $z z$ of Fig. 5. Fig. 8 is a plan or top view of a portion of the feed-bar, the auxiliary feed-bar, and feed-dog, the latter being in section on line $y y$ of Fig. 4. Fig. 9 is a vertical end view of a portion of the feed-bars and feed-dog, parts being in section on line xx of Fig. 4.

Similar letters of reference represent corresponding parts in all the figures.

A represents the bed of the crocheting or overseaming machine and forms the support for the principal working and other parts, and also forms the work-plate or table. Supported in bearings B, beneath the bed A, is the main driving-shaft C, to which is secured the wheel D, adapted to have motion imparted to it by hand or by any other conven-

ient means to operate the machine. To the main shaft C is secured an eccentric integral 55 with the cam-cylinder R, which, together, operate the needle s^2 , through the eccentric-rod S, the needle-lever s , and needle-bar s' , and also operate the looping mechanism consisting, principally, in the angle-lever T, the straight 60 lever t , the hook-bar guide t' , the hook-bar t^2 , with its slotted head t^3 , and guide t^4 , and crochet-hook t^5 . U is the presser-foot bar, to the lower end of which is secured the presser-foot u. The finger-plate a is provided with 65 a finger a' and slot a^2 .

The parts hereinbefore specifically mentioned comprise the principal portion of a crocheting or overseaming machine which forms the subject of my application for Letters Patent filed on January 18, A. D. 1886, Serial No. 188,912, and to which reference may be had for a more complete description.

The feeding mechanism, hereinafter described and claimed, is shown as applied to a 75 crocheting or overseaming machine similar to the one above herein referred to; but such feeding mechanism may be applied to other machines.

Upon the main shaft C is secured the principal feed-bar cam E, which, in conjunction with the spring F, operates the principal feed-bar G, said feed-cam E acting upon the projection g' , depending from the lower side of said principal feed-bar G in proximity with 85 said feed-cam E. The principal feed-bar G is supported in bearings upon the bed A in such a manner that the said feed-bar may be reciprocated longitudinally in said bearings. Near one end of the principal feed-bar G is a 90 small projection g^2 , which is brought into contact with the end of the screw f, when the spring F is allowed to operate, as will be more fully explained hereinafter. The screw f, which is screwed through a portion of the 95 bed A, adjustably limits the distance to which the principal feed-bar G can be drawn horizontally in a direction toward said screw f by the action of the spring F, and the direction mentioned will, for convenience, herein-after be called the "backward" direction of said principal feed-bar G, while motion in the opposite direction will be called the "forward" motion or direction. A groove or way g^4 is made vertically across the enlarged portion or head 105 of the principal feed-bar G, which groove g^4

forms a guide for the feed-dog g^5 , said feed-dog g^5 being adapted to be reciprocated in said groove g^4 , as will be further explained.

H is an auxiliary feed-bar, pivoted to the 5 projection g^3 on the upper side of the principal feed-bar G by means of a stud or screw h . The opposite end of the said auxiliary feed-bar H is turned or bent upward, and is provided with a stud or pin h^4 , for a purpose 10 which will hereinafter be fully explained. The auxiliary feed-bar H passes under and is loosely held by the cap h^2 , secured to the principal feed-bar G by the screws h^3 h^3 . By this construction the feed-dog g^5 is held in its 15 groove g^4 , and receives a vertical reciprocating motion from the auxiliary feed-bar H through the screw h' , which passes through the slot h^6 in the auxiliary feed-bar H and screwed into the said feed-dog g^5 . The auxiliary feed-bar H receives its vertical reciprocating motions from the pin l^3 in a slot h^5 in said auxiliary feed-bar H, in a manner about to be explained.

Secured firmly to the main shaft C at one 25 of its outer ends is a pinion or toothed wheel I, gearing into the larger toothed wheel J, the latter being held to the bed A by the shoulder screw or stud j , upon which stud the said toothed wheel J may be rotated. Attached 30 to the side of the toothed wheel J is a pattern wheel or disk K, having a projection k upon its periphery, said projection k being formed with a grade or incline k' at one of its ends. Pivoted to the bed A upon a stud 35 or screw l is a lever L, provided with a projection or pin l' , located nearly over the center of the pattern-wheel K and resting upon the edge thereof. Near one end of the lever L and adjustably secured to it by the nut l^4 is 40 a stud or pin l^3 , which extends through an aperture a^4 in the bed A and into the slot h^5 in the auxiliary feed-bar H, as hereinbefore mentioned. The coiled wire spring F is connected at one of its ends to a pin f' , extending downwardly from the bed A, while the other end of said coiled wire spring F is connected with the auxiliary feed-bar H through a hole f^2 in said auxiliary feed-bar H. On account of the angular or diagonal position 45 of the spring F its force is exerted in a downward and backward direction upon the auxiliary feed-bar H and its connected parts. When the pin l' rests upon the projection k of the pattern-wheel K, the lever L, the auxiliary feed-bar H, and consequently the feed-dog g^5 , will be held in their highest or upward 50 positions, with the teeth of said feed-dog g^5 , extending slightly above the work-plate through the slot a^3 in the finger-plate a to 55 engage the fabric, as is common in sewing-machines; but when the pin l' is resting upon the surface k^3 of the pattern-wheel K the lever L, the auxiliary feed-bar H, and therefore the feed-dog g^5 , will be in their lowest or 60 downward positions.

It will be seen that the pattern-wheel K governs the position vertically of the feed-

dog g^5 . The pattern-wheel K is here shown as circular in form, except at the projection k , and at all other parts acts simply as a stop 70 to prevent the further downward motion of the pin l' and its connected parts. It is obvious that any stationary stop for the pin l' or any of its connected parts may be used as well. Further, I do not confine myself to the 75 particular pattern shown nor to the exact relative sizes of the toothed wheels or gears.

The feed-dog g^5 may be adjusted vertically somewhat by means of the adjustable stud or pin l^3 , which may be moved upward or 80 downward by loosening the nut l^4 , the hole through which the pin l^3 passes in the lever L being somewhat larger than the said pin l^3 at that point.

In the mechanism shown the feed-cam E 85 rotates, and with the action of the spring F causes the principal feed-bar G, together with the attached parts, to reciprocate horizontally five times forward and backward to each revolution of the pattern-wheel K, the toothed 90 wheel J, which carries said pattern-wheel K, being five times as large as the small gear I; hence the feed-dog is carried five times forward and five times backward, but only once up and once down to each complete rotation 95 of the toothed wheel J with its pattern-wheel K.

The cam E should be so timed in relation to the projection k on the pattern-wheel K that the pin l' will be caused by the rotation of 100 shaft C to rise upon the incline or grade K' of the said projection k at a time after the feed-dog g^5 has moved to its extreme backward position, in which backward position the feed-dog g^5 will then be raised vertically 105 to its highest or operative position in readiness to carry or feed the fabric forward by the further rotation of the shaft C, the fabric having been placed between the presser-foot u and finger-plate a . The projection k 110 upon the pattern-wheel K should be made of such length as to pass by the pin l' and allow the action of the spring F to carry said pin l' down to its lowest position, (in case it should fail to drop by its own gravity,) and 115 with it the feed-dog g^5 , at a time soon after the said feed-dog g^5 has reached its extreme forward position, so that when it returns to its backward position it will not engage the fabric.

It is obvious that the feed-dog g^5 should engage the fabric and carry it forward while the needle s^2 is out of said fabric.

In the arrangement shown and described it will be seen that the needle s^2 and the looping mechanism belonging with said needle s^2 125 will be operated five times, while the fabric being placed with its edge under the presser-foot, as explained, will remain stationary, and that after the fifth loop has been formed, (the needle s^2 having been previously supplied with thread,) and while the needle is above and out of the fabric, the said fabric will 130 then be fed along one step, the length of

which step being the distance to which the feed-dog g^5 carries said fabric during the whole of one forward motion of said feed-dog g^5 . Five loops will therefore be formed 5 around the finger a' upon the edge of the fabric, each of said loops passing through or connected to the fabric at very near the same point. The tendency then is for the loops to be formed over and upon each other, and, 10 after several loops have been formed, the hook t^5 , which forms said loops, has a great tendency to become entangled in the superimposed loops. The loops also will be made of uncertain size.

15 To obviate the difficulties mentioned, a supplemental apparatus is provided to push or carry along the loops slightly without materially moving the fabric and thus carry said loops out of the path of the looping-hook t^5 20 and modifying the loops, as will be more fully explained.

The construction and co-operation of the supplemental feeding mechanism are as follows, viz: M is a supplemental finger-plate 25 loosely held in the groove m in the bed A by means of two gibs or caps $m' m'$, which caps are held to the said bed A by screws m^2 . The supplemental finger-plate M is made at its forward end in an irregular form somewhat 30 resembling the ends of two fingers placed closely together, the finger m^3 being slightly longer and somewhat smaller than the finger m^4 , such form not being necessary, but deemed advantageous. The supplemental finger-plate 35 M is further provided with pins $m^5 m^6$, which are of use in limiting the longitudinal throw, which the said supplemental finger-plate is adapted to have imparted to it. The caps $m' m'$ act as stops for the pins $m^5 m^6$. Made integral (in this case) with the supplemental finger-plate M is the dependent portion N, which forms a support for the shoulder n and the latch n^2 , which latch n^2 is loosely held in 40 the slot n' by means of the pin n^3 . The flat 45 spring n^4 , secured to the support N by the screw n^5 , exerts its force to hold the latch n^2 in position shown, the pin n^6 being a stop to limit the motion of the said latch n^2 in the direction in which the spring n^4 carries said 50 latch. The mechanism dependent from the bottom of the supplemental finger-plate M, I have named the "lock." This lock is adapted to engage the stud h^4 (hereinbefore mentioned, but the use of which is not explained)

55 when said stud h^4 is in its lowest and most backward position, but not when said stud h^4 is in its highest position. The stud h^4 is carried forward and backward with the auxiliary feed-bar H at every rotation of the cam E, 60 and will be in its lowest position at all times, except during one out of every five of its forward movements, at which time the said stud h^4 will move forward after it has been raised to its highest position, as has been explained.

65 In Fig. 4 the upturned end of the auxiliary feed-bar H, which carries the stud h^4 , is shown in its highest and most forward position by

the solid lines, while the dotted lines show other positions of said feed-bar and stud, as will be explained. Commencing at the position shown by the solid lines in Fig. 4, the auxiliary feed-bar H will next be carried downward to the position shown by the dotted lines and marked H', thence backward to the dotted position H², and during its backward 70 passage the outer or flattened end of the stud h^4 will be brought into contact with and slide along the inclined edge of the latch n^2 , pressing said latch n^2 into its groove n^2 ; but after the passage of the said pin h^4 by the projecting end of the said latch n^2 said latch will be brought into its normal position by the action of the spring n^6 . The auxiliary feed-bar H will then be moved forward and backward 75 several times while in its lowest position, carrying forward the supplemental finger-plate M when the pin h^4 comes into contact with the projecting end of the latch n^2 and carrying said supplemental finger-plate M backward 80 when the said pin h^4 comes into contact with the rigid shoulder n. As has already been stated, the auxiliary feed-bar H will be carried from its lowest position to its highest at a time after it has reached its most backward position, and the dotted lines marked H² represent 85 the latter position. From this point the auxiliary feed-bar H will be raised to the position of the dotted lines marked H³ after it has completed a series of reciprocations in its lowest position, and thence be carried forward to the extent of its throw, moving the pin h^4 along in a path over and above the latch n^2 . The lock, together with the supplemental finger-plate M, will therefore be left behind and remain stationary and in its most 90 backward position. At the time when the supplemental finger-plate M remains stationary the feed-dog g^5 will operate to feed along the fabric, said feed-dog g^5 being carried forward in its highest position. 95

Having carefully described and explained the construction and operation of the various parts of mechanism included in my present invention, and also having in general explained the machine to which such mechanism 100 is applied, I will briefly describe the co-operation of various parts and the result of such co-operation.

It will be supposed, for convenience, that the needle s^2 has been supplied with thread; 105 that the fabric has been placed between the presser-foot u and finger-plate a, with the edge of said fabric upon the finger a' , and that loops have already been formed for a short distance along the edge of said fabric by the 110 looping mechanism. If now the main shaft is rotated, carrying with it the various parts which are secured to said shaft, the feed-cam will at the proper time carry forward the principal feed-bar and the parts thereto connected. 115 The small toothed wheel will rotate and revolve the larger toothed wheel with the pattern-disk, while the needle s^2 , together with the looping mechanism, will also be in operation. 120

While the loops are being formed upon the edge of the fabric, the supplemental finger-plate will be carried forward and back, (excepting one stitch in every set of five stitches or loops,) dwelling for a short time at each end of its throw, pushing or feeding forward the loops sufficiently to clear them from the looping - hook, and remaining forward long enough to have a new loop formed around or over the larger part of the forward end of the supplemental finger-plate at the proper time. The supplemental finger-plate remains backward while one stitch or loop is formed around the small stationary finger-plate, which loop will therefore be smaller or shorter than the other loops of the series, and will be formed at the time when the fabric is fed forward, which has a tendency to make the border narrower and less prominent at that point.

I prefer to finish the edge of the fabric first with one course of plain or regular crocheted loops and add the new and improved border upon the plain finish very near the edge of the fabric or even outside of the original fabric.

Having thus stated my invention, I now claim—

1. In a machine of the character specified, the combination of the following mechanisms: a stitch-forming mechanism provided with a thread-carrier and a looper, the latter co-operating with the thread-carrier to engage the thread on alternately-opposite sides of the fabric and draw loops thereof to or beyond the edge of the fabric and interloop the ends of said loops, and an intermitting-feed mechanism engaging the fabric to advance the latter only after the formation of two or more complete stitches by the stitch-forming mechanism, substantially as described.

2. The combination, in a machine such as described, and with a reciprocating thread-carrying needle, a looper engaging the needle-thread alternately on opposite sides of the fabric to draw and interloop said thread along the edge of the fabric, and a fabric-feeding device operating upon the fabric to advance the latter only after several reciprocations of the needle, of a system of driving mechanism, substantially such as described, connecting the needle-looper and feeding mechanism in a manner to cause the feeding devices to operate upon the fabric to advance the latter after a series of stitches have been formed and while the needle is withdrawn from the fabric and a loop of the thread held by the looper.

3. In a machine such as described, and in combination with a stitch-forming mechanism comprising a thread-carrier and a looper co-operating to form stitches around the edge of the fabric, a reciprocating feed-dog held in inoperative relation to the stitch-forming mechanism during the formation of a series of stitches and brought into operative relation with the fabric at intervals occurring be-

tween successive series of stitches, substantially as described.

4. The combination, in a machine such as described, and with a thread-carrier and a looper co-operating therewith to form loops around the edge of the fabric and interloop said loops, of a reciprocating feed-dog held normally from contact with the fabric during the formation of a series of loops by the thread-carrier and looper, with mechanism for elevating said feed-dog into contact with the fabric to feed the latter after a cluster of loops have been formed.

5. In a machine such as described, the combination, with the reciprocating needle and looper, with means for reciprocating said looper alternately above and beneath the fabric to engage the thread and draw loops therefrom to or beyond the edge of the fabric, of a loop-feeding device engaging the loops beyond the edge of the fabric, and means for actuating said loop-feeding device, whereby a series of loops are formed while the fabric remains stationary.

6. The combination, with a reciprocating needle and a looper reciprocating alternately above and below the fabric to engage the needle-thread on opposite sides of the fabric, of a feeding device engaging the fabric and a loop-feeding device arranged and operating beyond the edge of the fabric to engage the loops thereon, substantially as described, whereby after a series of loops is formed the fabric is fed to spread the cluster.

7. In a machine such as described, the combination, with a thread - carrying needle, a looper co-operating therewith, and a fabric feed operating at intervals between successive series of reciprocations of the needle, of a finger around which the loops are formed, and a loop-feeding device engaging the loops upon said finger, substantially as described.

8. In a machine such as described, the combination, with a stitch - forming mechanism comprising a thread-carrying needle and a looper co-operating therewith to engage the thread alternately above and beneath the fabric, and draw-loops beyond the edge of the latter and interlooping said loops at their outer ends, a fabric feed engaging the fabric only after a series of stitches have been formed, of a finger adjacent the needle around which the loops are drawn, and a loop-feeding device located beyond the edge of the fabric and engaging the loops, substantially as described.

9. A stitch-forming mechanism comprising a thread-carrier and a looper, and a finger around which the stitches are formed, in combination with a feeding device engaging the stitches on the finger, substantially as described.

JOSEPH M. MERROW.
